UNITED STATES PATENT OFFICE

166,716

REFRIGERATOR CABINET

Ray C. Sandin, Oak Park, Ill., assignor to Hot-point Inc., a corporation of New York

Application December 30, 1950, Serial No. 13,639

Term of patent 14 years
(CL. D67—3)

To all whom it may concern:

Be it known that I, Ray C. Sandin, a citizen of the United States, residing at Oak Park, in the county of Cook and State of Illinois, have invented a new, original, and ornamental Design for a Refrigerator Cabinet, of which the following is a specification, reference being had to the accompanying drawing, forming a part thereof.

In the drawing, Fig. 1 is a front perspective view of a refrigerator cabinet, showing my new design; Fig. 2 is a side elevation of the door of the refrigerator cabinet; Fig. 3 is a plan section of said door taken on lines 3—3 of Fig. 1; Fig. 4 is a front elevation of the left hand half of the door trim strip, the right hand half being identical therewith; and Fig. 5 is a side sectional view of the trim strip taken on the lines 5—5 of Fig. 4.

The dominant features of the design reside in the portion shown in full lines.

I claim:

The ornamental design for a refrigerator cabinet, substantially as shown and described.

RAY C. SANDIN.
